UNITED STATES PATENT OFFICE.

BARTON H. COFFEY, OF BOSTON, MASSACHUSETTS.

SUBAQUEOUS ROCK-BREAKER.

No. 918,968.

Specification of Letters Patent.

Patented April 20, 1909.

Application filed August 22, 1908. Serial No. 449,801.

To all whom it may concern:

Be it known that I, BARTON H. COFFEY, a citizen of the United States, residing at Boston, in the county of Suffolk and State of Massachusetts, have invented a new and useful Improvement in Subaqueous Rock-Breakers, of which the following is a specification.

The object of my invention is to provide an improved form of rock-breaker based on the principles of my broad patent of September 11, 1900, No. 657515; reissued June 26th 1906, No. 12501, wherein a caisson or tube from which the water is excluded, surrounds the rock-breaking machinery, thus eliminating all water resistances. In the first form practically used, a heavily weighted chisel was elevated and dropped through the tube upon the reef; and where the chisel landed on sloping surfaces of rock, violent side impacts were delivered to the steel walls of the tube tending to crystallize and disrupt them. Also in certain varieties of rock a fine sand is formed in the breaking process, which entered the tube, clogged the action of the chisel and detracted from the efficiency of the apparatus. To avoid these defects I place a guide on the lower end of the tube or caisson, so held that its axis always remains in line with the axis of the tube, and provided with openings for the escape of compressed air, the guide in turn supporting a chisel, whose axis coincides with its own. A heavy weight or hammer in the tube, is elevated and dropped upon the chisel, driving it into the rock. It is obvious that no matter what character of surface the point of the chisel rests upon, the hammer blow must be transmitted in a straight line through the axes of the connected parts, resulting in the elimination of all side impacts.

The form of caisson employed in the apparatus described and claimed in this specification, is known as the pneumatic type, and may be defined as a partially submerged structure, embodying an air and water tight vessel to which compressed air is supplied, and from which it is discharged, through appropriate openings; the air pressure thus necessarily maintained, keeping all spaces within the vessel above the level of the discharge openings, free from water. See *Century Dict.*—Caisson; *Ency. Brit.*, 9th edition, Caisson. *Patton's Civil Engineering*, Ed. 1895, paragraph 430, *et seq.*

I am aware of a proposal to operate a

chisel through a water tight joint at the lower end of a tube, thus forming a closed vessel, which is not a pneumatic caisson. In practical work, such provisions are unnecessary, very little sand is formed, and a strong issuing current of air effectually prevents the entry of any sand, mud, etc. through contracted openings at the lower end of a pneumatic caisson, and as the air pressure within the caisson must equal the hydrostatic pressure without, before air escapes, water is automatically excluded.

This construction eliminates the necessity of maintaining tight joints and accurate fits, which is obviously a difficult problem, when the enormous vibratory strains and shocks the parts are subject to, from the repeated blows of falling weights of from ten to twenty tons, are considered.

Another advantage is, that the air pressure within the caisson can never exceed the hydrostatic pressure outside, any increase in the volume of air entering, simply causing an increased outflow through the openings in the lower end of the caisson and guide, without any rise of pressure. I am thus enabled to employ the large volumes of air I find advantageous for other purposes, described later on. In my preferred construction Figures 1, 2 and 3 it is clear that a rise of pressure would cause an increased upward reaction upon the caisson, tending to lift it from the guide, and thus destroy the proper action of the apparatus. In actual operation the depth of immersion is constantly changing, due to varying depths of bottom, rise and fall of tide, hoisting the caisson, etc., etc. In my apparatus the air pressure obviously automatically adjusts itself to these varying conditions, whereas in a closed vessel, some complicated device would be necessary to effect the same end.

Another advantage consists in the power of the issuing air currents to create water currents in the vicinity of the chisel, and sweep away mud, sand and other material, almost invariably found overlying ledges and reefs. For this purpose I use volumes of air largely in excess of that necessary to keep the caisson clear of water.

Another advantage over the closed vessel, lies in the complete absence of any water whatever in the caisson so long as the air is escaping from the lower end, which is obviously conducive to high efficiency; and this desirable condition is constantly visible to

the operating force by means of the air bubbles rising to the surface of the water. In the closed vessel considerable water might enter through leaky joints before detection.

5 The entry of broken rock through the openings in the guide is obviously impossible, as the openings are above the level of such rock, at the extreme penetrations permissible with a given length of chisel, as shown at 10 Fig. 3.

15 The maintenance of an air pressure within the caisson insures that any leakage whatever will take place from within out, the tendency therefore being to prevent the entry of gritty substances between the movable surfaces; a point of great practical importance with reference to wear and tear.

20 Another advantage of openings at the lower end of the caisson consists, in their forming an outlet for the escape of water that has entered the caisson while standing idle without air pressure; as at night, Sundays and holidays. In the closed vessel any water must be pumped out, or the whole apparatus 25 raised above the water level and drained; whereas in my apparatus, the air pressure quickly forces the water through the openings until the caisson is free. Thus the same agency that keeps water from entering the 30 caisson, also empties it.

Reference now being had to the drawings:—Fig. 1. is an end view of the hull or float supporting the rock-breaking apparatus, floating at the water line W—W and 35 showing the caisson in the working position marked Y., and the moving position in dotted lines marked Y¹. Fig. 2. is an elevation of Fig. 1. showing the hull and caisson in section on the center line of Fig. 1. Fig. 3. is 40 an enlarged view of the chisel my preferred form of guide and the lower end of the caisson; representing the conditions existing where the chisel has been driven to its extreme penetration. Fig. 4. is an alternate 45 form of construction shown also in section.

In detail 1, is the caisson, a vertical cylinder closed to the atmosphere and open at the lower end preferably of steel; supported by the guide 2, which embraces its lower end 50 with an easy fit, permitting vertical and rotary movement between the two. The guide 2, rests upon the chisel 3, with provision for relative vertical movement. The chisel 3, stands upon the reef and supports 55 all the parts in the working position Y, Fig. 1.

The assemblage is prevented from falling over by the pins 4, integral with the caisson, which are inserted in the guide shoes 5, which in turn slide freely on the vertical guides 6, 60 secured to the frame 7, in turn supported by the float 8, and over the well 9. The float 8 is held against horizontal movement by anchors or spuds (not shown).

The caisson is divided into two chambers, 65 by the diaphragm 10 integral with its walls.

The upper chamber is open to the atmosphere, the lower chamber is kept free from water and full of compressed air, by means of the air compressor 12, the pipes 13 and 14, and flexible hose 15, the compressed air escaping at the openings 16 in the guide 2. Other gas than air can be used for the same purpose. 70

In the lower chamber of the caisson and free to reciprocate vertically, is the weight or hammer 17, loosely fitting the walls of the caisson at the rings 18, and provided with passages 19 for the movement of air, during its elevation and fall. The hammer is lifted by the rod 20, passing into the upper chamber of the caisson through the stuffing box 11, and terminating in the barbed end 21. Upon falling the hammer strikes the cap 22 of the chisel 3, which transmits its energy to the reef below. 75

80 The lifting apparatus consists of a boiler, engine and auxiliaries not shown and contained in that portion of the hull 8, broken away. The engine turns the drum 23, thus operating the cable 25, which passes over the sheave 26 and lifts or lowers the bell-mouthed clutch 27, fitted with the trip lever 28, and trip chain 29, which in turn is threaded around the sheaves 30, to bring the free end to the outside of the caisson for convenient operation. 85

When it becomes necessary to hoist the caisson, the guide 2, is prevented from dropping off, by the side chains 31, connecting the two, as clearly shown; the cap 22 serving to 100 support the chisel 3, under the same circumstances.

In the alternate construction Fig. 4. a guide 32 integral with the caisson 1, is employed; with openings 33, for the escape of 105 compressed air. In other respects the apparatus is similar to that already described.

The operation of the machine is as follows:—After the float 8 is moored over the reef, either by anchors or spuds (not shown) 110 the caisson is lowered until the chisel 3, rests upon the rock. In this position it will be observed the entire weight of the connected parts is upon the rock. The clutch 27 is then lowered over the barbed end 21 of the 115 rod 20, engaging same; the clutch is then hoisted raising the hammer 17, to any desired point within the limit of the machine (as the position X¹, Fig. 2, shown in dotted lines) when a pull on the trip chain 29, releases the clutch and permits the hammer to fall and strike the cap 22, forcing the chisel 3, into the rock. When sufficient depth is so obtained at any desired point, the hammer is clutched and raised until it engages the lower 120 side of the diaphragm 10, on further hoisting, the caisson, guide and chisel lift also, sliding vertically in the guides 6, until the position of Y¹, Fig. 1. is assumed; the chisel 3, being then clear of the ledge, the float 8, can be 130

moved to a fresh position, the chisel again lowered to the rock, and breaking operations resumed.

As in my former patent referred to, the 5 leading feature of this invention consists in providing a caisson or cylinder means for keeping it free from water when submerged, so that the rock-breaking machinery can work unhampered by the water resistance.

10 As the details of this machine can be varied in many ways familiar to those skilled in the art, without departing from the spirit of my invention, I do not limit myself to the construction shown.

15 Many features of novelty disclosed herein and not referred to in the claims such as the movable guide or mouthpiece, will be specifically protected by other patents.

Having described my invention I claim—

20 1. In a subaqueous rock-breaker, the combination of a pneumatic caisson normally open at the lower end, and a chisel movably guided at the lower caisson end, the construction and arrangement of parts being 25 such as not to obstruct free and continuous air escape at the lower caisson end, a hammer adapted to reciprocate within the caisson and strike the chisel but not attached to same, means to reciprocate the hammer and means 30 for forcing compressed air into the caisson to exclude water, sand, mud, etc. for the purposes set forth.

2. In a subaqueous rock-breaker, the combination of an upright tubular member, a 35 hammer movable therein and substantially occupying the entire cross section of said tubular member, said hammer constructed with air passages connecting the air spaces below and above said hammer, and a chisel mov- 40 ably fitted at the lower end of said tubular member.

3. In a subaqueous rock-breaker, the combination of a pneumatic caisson normally 45 open at the lower end, and a chisel movably guided at the lower caisson end, the construction and arrangement of parts being such as not to obstruct free and continuous air escape at the lower caisson end, a ham- 50 mer adapted to reciprocate within the caisson and strike the chisel but not attached to

same, means to reciprocate the hammer and means for forcing compressed air into the caisson to exclude water, sand, mud, etc., in combination with a guide frame mounted on a float, adapted to hold the caisson upright 55 while permitting vertical movement of same; and means for lifting and lowering the caisson for the purposes set forth.

4. In a subaqueous rock-breaker, the combination of a pneumatic caisson normally 60 open at the lower end, and a chisel movably guided at the lower caisson end, the construction and arrangement of parts being such as not to obstruct free and continuous air escape at the lower caisson end, in combination with means for forcing compressed air into the caisson in excess of that necessary to exclude water, sand, mud, etc. for the purposes set forth.

5. In a subaqueous rock-breaker, the combination of a pneumatic caisson, a chisel movably guided at the lower caisson end, means for forcing compressed air into the caisson; and openings for the escape of compressed air placed above the level of broken 75 rock, for the purposes set forth.

6. In a subaqueous rock-breaker, a pneumatic caisson divided into two compartments by a diaphragm, openings from the upper compartment to the atmosphere, and 80 openings from the lower compartment for the escape of compressed air; in combination with a chisel movably guided at the lower caisson end; and means for forcing compressed air into the lower compartment, for 85 the purposes set forth.

7. In a subaqueous rock-breaker, the combination of a pneumatic caisson with its lower end fitted as a guide, a chisel movable upon said guide, a hammer reciprocating in 90 said caisson; and means for forcing compressed air into the caisson for the purposes set forth.

In testimony whereof, I have signed my name to this specification in the presence of 95 two subscribing witnesses.
